DESIGN FOR A DISPENSER FOR COSMETIC CREAMS

Robert Gordon Bau, North Hollywood, Calif.

Application September 23, 1944, Serial No. 115,437

Term of patent 14 years

(Cl. D58—8)

To all whom it may concern:

Be it known that I, Robert Gordon Bau, a citizen of the United States, residing in the city of North Hollywood, in the county of Los Angeles and State of California, have invented a new, original, and ornamental Design for a Dispenser for Cosmetic Creams, of which the following is a specification, reference being had to the accompanying drawing, forming part thereof.

Fig. 1 is a side view in elevation of a dispenser for cosmetic creams showing my new design.

Fig. 2 is a front view in elevation of the dispenser for cosmetic creams of Fig. 1.

Fig. 3 is a plan view of the dispenser for cosmetic creams of Fig. 1.

I claim:

The ornamental design for a dispenser for cosmetic creams, as shown.

ROBERT GORDON BAU.
